BREECH LOADING MORTAR

Isaac F. Rosenkrantz, Greenbelt, Md.

Application November 6, 1946, Serial No. 708,045

2 Claims. (Cl. 89—21)

(Granted under the act of March 3, 1883, as amended April 30, 1928; 370 O. G. 757)

1

The invention described herein may be manufactured and used by or for the Government for governmental purposes without the payment of any royalty thereon.

My invention relates to mortars, particularly to a breech loading mechanism for assembly on the tube of a standard muzzle-loading mortar to convert said mortar to one which may be loaded from the breech, and be fired by means of a hammer and spring plunger firing pin.

In the present art, a mortar, particularly one of large caliber, is not adapted for directional or low level fire. A mortar shell is ordinarily fired by dropping the complete round down the barrel or tube of the mortar. A primer in the shell hits the firing pin fixed in the base of the mortar to fire the round, the round being expelled from the tube by the pressure of the gases from the burning propellant. Thus, a mortar was restricted in firing upon targets where the elevation of the target was less than approximately 40 degrees because the shell would not gain sufficient momentum during its drop within the mortar tube to drive the firing pin into the primer of the shell. Firing on a target below the level of the mortar tube was, of course, out of question. For these reasons, and because it was also necessary for the loaders to be exposed to enemy fire when loading the mortar, muzzle-loading mortars could not be used efficiently in aircraft, or when mounted on a tank or an armored vehicle.

While my invention is adaptable to all types of mortars operated by drop fire in the manner described, it is in the present instance applied to the standard 81 mm. M1 muzzle loading mortar, and takes the place of the present means used for firing the said mortar, comprising a base cap with a spherical connection which is used to secure the tube on the base, and a fixed firing pin positioned in the cap. Briefly, my breech loading mechanism for mortars comprises a breech ring internally threaded to receive the mortar tube and externally threaded for engagement with a recoil mechanism, a slotted screw type breechblock mounted on a block carrier hinged to the breech ring, and having internal interrupted screw threads to engage corresponding threads in the breech ring, a firing mechanism of the continuous pull type, a ring shaped neoprene obturator, safety latch means to prevent firing the mortar until the breech is fully closed and locked, and restraining means to prevent a shell falling out of the mortar bore.

In the illustrated embodiment (Figure 1), the breech loading mortar is shown mounted on the

body of a tank, but it should be understood that this application is exemplary only, and that the breech loading mechanism of my invention may be applied to muzzle loading mortars of larger or smaller caliber, and that the converted mortar may also be arranged for mounting in aircraft, on any armed or unarmed vehicle, or upon a stationary mount for fixed or transitory emplacement.

10 A principal object of my invention is to provide a breech mechanism for mortars which will permit conversion of a muzzle loading mortar into one which may be loaded and fired from the breech end thereof.

15 An important object of my invention is to provide the mechanism of the character described which will permit firing of the mortar upon which it is used by means of a spring firing pin actuated by lever or trigger means.

20 Another important object of my invention is to provide a breech loading mechanism for mortars which will permit mounting the mortar in which it is employed upon aircraft, a tank, or an armored vehicle, so that the said mortar may be loaded and fired from within said aircraft or vehicle.

25 A further object of my invention is to provide a breech mechanism for mortars which will include safety means for preventing fire of the mortar while the breech is open or unlocked, will insure safe and proper closing of the breech, and which will retract the firing pin simultaneously with the opening of the breech.

30 Another object of my invention is to provide a breech mechanism for mortars which will include means for retaining a shell in the breech end of a mortar tube while the breech is open and the mortar tube is at a high angle of elevation, and which will prevent a shell dropping out of the muzzle end of the mortar tube when the said tube is pointed downward below the level of the mortar.

35 Still another object of my invention is to provide a breech mechanism for mortars which will be easy to load, safe to operate, and accurate in firing; which will have an efficient obturation system; which will not require special ammunition, and which will be simple to assemble and disassemble to permit cleaning and lubrication of the firing pin and other components.

40 50 Additional objects, advantages, and features of invention reside in the construction, arrangement and combination of parts involved in the embodiment of the invention, as will be understood from the following description and accompanying

drawings, forming part of the specification, wherein similar numbers are used to designate like parts throughout the specification and drawings.

In the drawings:

Figure 1 is a side elevation of a mortar embodying my invention mounted on the body of a tank,

Figure 2 is a vertical section through the breech mechanism of my invention with the breech closed but held in safe position while unlocked, the hammer being shown in elevation, and the handle and latch partly in elevation,

Figure 3 is an elevation of the closed and locked breech, with the hammer in firing position,

Figure 4 is a section taken on the line 4-4 of Figure 2,

Figure 5 is an elevation of the face of the disassembled breechblock.

Figures 6 and 7 are an elevation of the inner face and a longitudinal section, respectively, of the spindle,

Figures 8 and 9 are rear and side elevational views, respectively, of the firing pin retaining cap, and,

Figure 10 is a rear elevation of the breech ring.

Referring now to the drawings, Figure 1 shows a mortar designated generally by the numeral 11 pivotally mounted on the body of a tank 12 for elevation and depression, as indicated in the dotted lines. The mortar 11 comprises a barrel or tube 13 and the breech assembly of the invention, designated generally by the numeral 14. A ball and socket shield 15 is carried on the tank 12, and suitable recoil mechanism 16 is provided to absorb the recoil energy of the mortar 11 when fired. Since neither the mounting, housing 15, nor recoil mechanism 16 form any part of the invention, and are all old and known in the art, they are not further described.

The mortar breech assembly 14 of my invention comprises a breech ring 17, a breechblock 18, and the component parts of the firing and safety mechanism which will be described later.

Breech ring 17 is formed from one piece of alloy steel, with a pivot lug 22 of alloy steel welded on the bottom side thereof to form a pivot bearing for the breechblock assembly. The rear end is interiorly threaded to tightly engage, as at 20, opposed threads provided on the standard 84 mm. muzzle loading mortar tube 13, which has been altered at its breech end, as shown at 19, to provide a suitable seat for the obturator system, as will be hereinafter pointed out. The rear end is also exteriorly threaded, as at 21, to fit the recoil mechanism 16. A keyway 23 is provided at the right side of the front face to form a keeper for a handle latch as will be later pointed out. The front or breech end has internal interrupted threads 18 for engagement with similar threads on the breechblock for the seating of the said breechblock.

The breechblock 18 is formed from one piece of alloy steel. It contains the firing mechanism, and is supported on the pivoted carrier bracket 24 which provides a pivot for opening and closing said breechblock. The said bracket 24 is slotted and bored at one end to fit the pivot lug 22 on breech ring 17, and is held in position by a pivot pin 25, a retaining cap 26, and a plunger detent 27. A boss 27 at the other end of bracket 24 takes bearing in the said breechblock, and has a bore 49 for a purpose which will be hereinafter pointed out. Breechblock 18 is arranged with interrupted external threads 28 for engagement

with the mating threads 18' in the breech ring 17. It is provided with a longitudinal axial bore 29 to fit boss 27, and a communicating coaxial bore 30 of smaller diameter to allow passage therethrough of a spindle 31. Two V grooves 32 and 33 are provided in the face of the block and form the open and closed positions of a safety latch, as will be hereinafter pointed out, the groove 32 also forming a seat for a handle 35 constructed and arranged to engage therein, the said handle being adapted for opening and closing said breechblock. The handle is held in a positive position by two Allen head screws 36 threaded into the tapped holes 37 in the face of breechblock 18. Handle 35 is provided with a longitudinal slot 39 to receive a spring pressed latch 38 pivotally connected to said handle by pivot pin 43. Handle 35 and latch 38 are bored adjacent one of their respective ends to provide the opposed bores 40 and 41 in which a compression spring 42 is seated to provide means for retaining the latch in slot 39. The breechblock 18 is held in closed position by said spring latch 38 and can be brought to open position by a one-quarter revolution of the handle 35. An Allen head screw 44, threaded into a tapped hole 45 forms a stop for the breechblock 18 when it is opened.

Spindle 31 is formed of one piece of alloy steel, and it is held in position in boss 27 and breechblock 18 by means of a nut 46 threaded on one end thereof. A compression spring 47 surrounds an elongated section 48 of said spindle and is positioned in bore 49 of the boss 27. Opposed keyways 51 and 52 are provided in boss 27 and spindle 31, respectively, to receive a key 50 to positively hold said spindle 31 and prevent the said spindle turning in said bore.

The spindle 31 is provided at its other end with an out-flaring mushroom head 53 to engage within the breech end of mortar tube 13. The obturator means incorporated in the breech mechanism for sealing said breech mechanism against the gases of the burning propellant is positioned on stem 48 between the tapered rear surface of head 53 and the front face of breechblock 18. It comprises a circular steel disc 54, a rear slot ring 55, an obturator pad 56 of neoprene or similar resilient material engaged between said disc 54 and the rear surface of head 53, and a front split ring 57, the said split rings 55 and 57 and said obturator pad 56 forming a seal for the seat in the tapered end of mortar tube 13.

The spindle 31 is provided with an axial longitudinal bore 58 of varying diameters to receive a cylindrical firing pin 59 therein for reciprocal movement therethrough. The firing pin 59 is enlarged intermediate its ends to provide a thickened portion 60 adapted for sliding contact with a portion of the bore 58, and to provide a seat for a compression spring 61 positioned in said bore and about said firing pin. The forward end 62 of said firing pin is of reduced diameter to permit its passage through an aperture 63 in the forward end of the mushroom head 53, and a longitudinal slot 64 is provided adjacent its rearward end, the rearward end of said slot forming a shoulder 65.

The firing pin 59 and spring 61 are held in position in the bore 58 by means of a retainer cap 64 provided with two outstanding ears 65 at its forward end to engage within a portion of the bore 58 and allow reciprocal movement of said cap 64 relative to said bore. Cap 64 is also provided at

its rearward end with a circumferential flange 66 and an outwardly projecting finger 67. A slot 68 is provided in said flange 66 for a purpose which will hereinafter become apparent.

The hammer 69 is pivotally mounted on the carrier bracket 24 by means of a pivot pin 70. The hammer is provided with an enlarged head 71 in which a contact pin 72 is positioned, said pin 72 being adapted to strike against the rear end of firing pin 59 when said hammer 69 is suddenly pulled by means of a lanyard 73 attached to an outstanding finger 74 through a hole 75 provided therein.

The numeral 76 designates a safety latch to prevent firing the mortar until the breech is fully closed and locked. The top of the latch is adapted to position in slot 77 in firing pin 59 to retract said firing pin after firing of the mortar simultaneously with the opening of the breech by pressure against the shoulder 81', and to prevent the forward end 62 of the firing pin becoming stuck in the small aperture 63 in forward end of spindle 31 because of the corroding effect of the gases in the mortar tube 13. Safety latch 76 is pivotally mounted on a spring-urged bevel-headed pin 78 bearing in the carrier bracket 24 by means of a taper pin 88. A compression spring 79 is provided about the shank of the pin 78 between the beveled head of said pin and a shoulder formed in the bore 80 in which the pin is positioned. Positive vertical position is retained by said safety latch fitting in slot 68 in retaining cap 64. The beveled head of the pin 78 contacts the face of the breechblock at all times, and engages the V groove 33 in the face of the breechblock for safety and off positions. The latch 76 also acts as a stop for the hammer 69 when the breech is closed but unlocked, as is clearly shown in Figure 2.

A spring pressed plunger 81 is positioned in a bore 82 formed jointly in the breech ring 17 and lug 22, and is secured in place by means of a locking pin 83 slidable in a groove 84 in said plunger. The said plunger 81 is provided with a chisel top to permit said plunger to be forced into said bore 82 against the resistance of the spring 85 by the camming action of a shell against the taper of its top while said shell is being inserted into said tube. When said plunger is returned to its original position by the released energy of spring 85 it retains said shell in the mortar tube should the breech be open and the tube pointed in a high angle of elevation. A split snap-ring 85' is positioned in an annular undercut 86 formed in the interior surface of the tube 13 adjacent the breech end thereof, to prevent the shell falling from the muzzle of the tube when the said muzzle is depressed below the level of the mortar. The bore riders on the fin plates of the shell bear against said snap-ring and expand said ring in the undercut 86 when the mortar is fired.

In operation, the breechblock is released for withdrawal by a quarter turn of handle 35 after latch 38 has been pressed to release it from its engagement in keyway 23. The latch handle is then in the position indicated in the dotted lines in Figure 3, and may be pulled downward to withdraw breechblock 18 and its component assembly from engagement in the breech ring 17. In turning handle 35 the interrupted screw threads of the breech ring and breechblock, respectively, have been disengaged, and the firing pin 59, firing pin retainer 64, and safety latch 76 have moved rearward under the force of the released energies of their respective springs. Safety latch 75

76 is now in the safety position indicated in Figure 2, and acts as a stop for hammer 69. When handle 35 is pulled downward the entire breechblock assembly is withdrawn from the breech ring, and a new round may be inserted into the tube. Plunger 81 will hold the new round against falling out of the open breech if the tube is elevated, while snap-ring 85 prevents the round falling through the muzzle if the tube is depressed. The engagement of the beveled head of pin 78 in groove 34 prevents accidental turning of the breechblock while the breech is open. After the handle is lifted to close the breech, it is revolved again one-quarter turn to lock the breech, this locking movement also forcing the firing pin retainer and safety latch inward, and freeing the hammer from the restraint of the safety latch. The mortar is now in firing condition.

A feature of my invention is the ease with which the firing mechanism may be disassembled for cleaning or lubricating, and again assembled. To remove the firing pin, the safety latch 76 is raised as far as possible and turned right or left until it contacts the recessed portion of the carrier bracket 24. The retainer cap 64 is pushed in and rotated one-quarter turn to disengage the ears 65, and then pulled out. The firing pin and its spring may now be pulled out. To reassemble, the spring is placed on the firing pin and inserted in the spindle 31. The retainer cap is then placed on the firing pin, the ears 65 in line with the openings in the spindle, pushed until the cap comes to a stop, turned 90 degrees and pulled outwardly. The firing pin is turned so that the slot 77 is down and parallel with the center line of the breech. The safety latch is pulled upward swinging it into vertical position and deposit in the slot 68 of the retainer cap. Assembly or disassembly of the firing pin can be done in a few seconds time without the use of any tool.

Disassembly and assembly of the entire mortar is equally simple. With the breechblock closed, the spindle nut and spring are removed. With the breech open 90 degrees, the breechblock may be removed from the carrier bracket by pushing in on plunger detent 87 and sliding the cap 26 to one side. Then, the spindle and component parts of the obturator system may be readily withdrawn from the breechblock. The safety latch 76, pin 78 and spring 79 are disconnected and removed by withdrawing taper pin 88. The only tool required is a screw driver, if it is necessary to remove the handle 35. To reassemble, it is necessary only to reverse this process.

I have disclosed the invention in the best construction known to me, but it will nevertheless be understood that this is purely exemplary, and that changes and modifications in the construction, arrangement and combination of parts otherwise than as specifically claimed, and substitution of materials and equipment, mechanical or otherwise, may be made without departing from the spirit of the invention set forth in the appended claims.

Having thus described my invention, I claim:

1. Breech mechanism comprising a breech ring and a rotatable breechblock, firing means associated with said breechblock, a carrier bracket pivotally mounted on said breech ring, a hammer mounted on said bracket, and stop means resiliently mounted on said bracket, said stop means restraining said hammer until said breech mechanism is in fully locked position.
2. Breech mechanism comprising a breech ring

and a rotatable breechblock, a firing pin recipro-
cally mounted in said breechblock, a carrier
bracket pivotally mounted on said breech ring, a
firing hammer carried on said bracket, a spring
plunger safety latch carried on said bracket, said
safety latch engaging said breechblock and hold-
ing said breechblock in safe position when un-
locked, stop means formed on said safety latch to
prevent said hammer striking said firing pin while
said breechblock is in opened or unlocked closed 10
position, said safety latch constructed and ar-
ranged to retract said firing pin simultaneously
with the movement of said breechblock from its
engagement with said breech ring.
